UNITED STATES PATENT OFFICE.

ACHILLE MONIOT, OF PHILADELPHIA, PENNSYLVANIA, ASSIGNOR TO ARCHIBALD CAMERON AND JOHN ZIMERMAN, OF SAME PLACE.

DESIGN FOR A TABLE-COVER.

SPECIFICATION forming part of Design No. 18,690, dated October 16, 1888.

Application filed September 24, 1888. Serial No. 280,241. Term of patent 3½ years.

To all whom it may concern:

Be it known that I, ACHILLE MONIOT, a citizen of the United States, residing at Philadelphia, in the county of Philadelphia and State of Pennsylvania, have invented and produced a new and original Design for a Table-Cover, of which the following is a specification, reference being had to the accompanying photographic print, forming a part thereof, which 10 conveys to any one skilled in the art a clear understanding of the same, and is sufficient to enable such persons to use my invention.

What I claim as my invention, and desire to secure by Letters Patent, is—

The design for a table-cover, consisting in 15 the ornamentalations shown in the photographic print accompanying this specification.

ACHILLE MONIOT.
